UNITED STATES PATENT OFFICE.

SYDNEY S. EDWARDS, OF WILLIAMSTOWN, MASSACHUSETTS.

LOOM-SHUTTLE.

SPECIFICATION forming part of Letters Patent No. 394,915, dated December 18, 1888.

Application filed June 21, 1888. Serial No. 277,730. (No model.)

To all whom it may concern:

Be it known that I, SYDNEY S. EDWARDS, a citizen of the United States, residing at Williamstown, in the county of Berkshire and State of Massachusetts, have invented new and useful Improvements in Loom-Shuttles, of which the following is a specification.

In cop or loom shuttles having a flat spring to engage and hold the spindle-head a serious objection resides in the fact that the free end of the spring injures the paper tube, and also the yarn if the latter is wound low down or near the end of the tube, for the reason that the tube or the yarn comes into direct contact with the end of the spring whenever the cop is changed, thereby cutting the tube or the yarn, if the latter be wound low down, as stated. This will be obvious by stating that in shuttles of the character described the usual spindle-head is pivoted and the extremity of the flat spring extends over and bears by its flat under side directly upon such head sufficiently beyond the pivot of the latter to retain the spindle and cop in proper position within the shuttle. To apply a cop, the spindle is turned on the pivoted head, the latter riding under and forcing out the free end of the spring. The cop-tube is then forced down upon the spindle as far as possible, and if the yarn is wound so low down as to cover the paper tube the yarn will be injured by forcible contact with the free end of the spring, while if the tube be exposed the injury will be done to the tube itself.

The object of my invention is to avoid the objections stated without greatly increasing the cost of manufacturing the shuttles; and to such end the invention consists, essentially, in the combination, with a shuttle-body and a spindle-head, of a spring-plate having adjacent to its free end a depending lug, rib, or projection which bears upon the spindle-head in such a manner that when the spindle is turned out of the shuttle the head, acting on the lug or rib, forces the free extremity of the spring-plate outward and holds such free extremity at such distance from the head that when the cop-tube is forced down upon the spindle neither it nor the yarn will come into contact with the free extremity of the spring.

The invention also consists in the combina-

tion, with a shuttle-body and spindle-head, of a reversible spring-plate having adjacent to each end a lug or rib to bear on the spindle-head and hold either free extremity of the spring-plate from coming in contact with the paper tube or the cop, all as hereinafter more fully set forth.

In the accompanying drawings, Figure 1 is a broken top plan view of a cop or loom-shuttle embodying my invention; Fig. 2, a sectional view taken on the line *a a*, Fig. 1; Fig. 3, a similar view showing the position of the parts when the spindle is turned out of the shuttle-body and the cop forced thereupon, and Fig. 4 a detail perspective view looking at the under side of the spring-plate.

In order to enable those skilled in the art to make and use my invention, I will now describe the same in detail, reference being made to the drawings, wherein—

The numeral 1 indicates the body of a cop or loom shuttle of any construction suitable for the purposes required; 2, the eccentrically-pivoted spindle-head; 3, the paper tube, and 4 the cop. The shuttle-body is furnished with a recess, 5, containing the flat spring-plate 6, detachably connected at its center to the shuttle-body through the medium of a screw, 7, passing through an orifice, 8. The spring-plate on its under side, over the spindle-head, is formed or otherwise provided with a depending lug, rib, or projection, 9, which bears upon the upper side of the head, and is here shown as a rib extending transversely across the plate a distance from its extremity, so that when the parts are in the position shown in Fig. 3 such free extremity will rest on the head beyond the pivot-point, being indicated by dotted lines, Figs. 2 and 3. The spring-plate is detachable, and the pressure exerted on the spindle-head can be varied by adjusting the screw. To apply a cop, the spindle is turned out and the paper tube is forced down upon the spindle, as shown in Fig. 2; but as the spindle-head acts on the depending lug or rib 9 the free extremity of the spring-plate is held away from the spindle-head at such distance that the paper tube cannot come in contact with and be cut or otherwise injured by the free extremity of the spring; nor can the yarn be injured by the latter if wound down

upon the tube to cover the end portions thereof. By continued use the end of the spring-plate in action on the spindle-head will lose its tension or inherent elasticity, and to 5 render the plate efficient for a longer time I make said spring-plate reversible and provide a lug or rib, 9, near each end, so that when desired the plate can be reversed end for end, and this other lug brought into action. To 10 accommodate the lug remote from the spindle-head, I provide the bottom wall of the cavity 5 with a recess, 10, to receive said lug.

Having thus described my invention, what I claim is—

15 1. The combination, with a shuttle-body and a spindle-head, of a spring having a lug to bear on the head and hold the free extremity of the plate from contact with the cop-tube, substantially as described.

2. The combination, with a shuttle-body 20 and a pivoted spindle-head, of a spring-plate having on its under side a depending lug to bear on the head and hold the free end of the plate from contact with the cop-tube when the spindle is swung out of the shuttle, substantially as described.

3. The combination, with a shuttle-body and a spindle-head, of a reversible spring-plate having a lug adjacent to each end to bear on the head, substantially as and for the 30 purpose described.

In testimony whereof I affix my signature in presence of two witnesses.

SYDNEY S. EDWARDS.
